(57) **CLAIM**

The ornamental design for a hand held electronic device with keyboard and auxiliary input, as shown and described.

DESCRIPTION

FIG. 1 is a front perspective of a handheld electronic device in accordance with our design;

FIG. 2 is a back elevation of a handheld electronic device in accordance with our design;

FIG. 3 is a left side elevation of a handheld electronic device in accordance with our design;

FIG. 4 is a right side elevation of a handheld electronic device in accordance with our design;

FIG. 5 is a top plan of a handheld electronic device in accordance with our design;

FIG. 6 is a bottom plan of a handheld electronic device in accordance with our design;

FIG. 7 is a front elevation of a handheld electronic device in accordance with our design;

FIG. 8 is a front perspective view of a second embodiment of a handheld electronic device in accordance with our design; and,

FIG. 9 is a front elevation view of a second embodiment of a handheld electronic device in accordance with our design.
